[57] **CLAIM**

The ornamental design of a torchiere lamp with tent shade task light on swing arm, as shown and described.

DESCRIPTION

FIG. 1 is a side view of the torchiere lamp having a tent shade task light on a swing arm, the lamp being in combination with a tray (the opposite side being a mirror image thereof);

FIG. 2 is a front view thereof;

FIG. 3 is a rear view thereof;

FIG. 4 is a top view thereof;

FIG. 5 is a bottom view thereof;

FIG. 6 is a plan portion view thereof showing the arm in an alternate position;

FIG. 7 is a side view of an alternative embodiment thereof which eliminates the tray;

FIG. 8 is a front view thereof;

FIG. 9 is a rear view thereof;

FIG. 10 is a top view thereof;

FIG. 11 is a bottom view thereof; and,

FIG. 12 is a plan portion view thereof showing the arm in an alternate position.
